UNITED STATES PATENT OFFICE.

LOUIS SOOS, OF BUFFALO, NEW YORK.

SWEEPING-MACHINE.

971,158.

Specification of Letters Patent. Patented Sept. 27, 1910.

Application filed January 5, 1910. Serial No. 536,495.

To all whom it may concern:

Be it known that I, LOUIS SOOS, a subject of the Emperor of Austria-Hungary, residing at Buffalo, in the county of Erie and State of New York, have invented new and useful Improvements in Sweeping-Machines, of which the following is a specification.

This invention relates to a street sweeper of that type in which the dirt is swept direct from the street into a cart or wagon which carries the sweeping mechanism and which may be dumped in any suitable locality to which the load has been transported.

One of the objects of this invention is to provide a sweeping mechanism in which the brushes can be lifted from the ground and doubled so as to render the machine more compact when the same is used only for transporting a load of dirt.

Another object of this invention is to provide improved means for dumping the load of sweepings.

My invention has the further object to enable the curb of the street to be swept effectively.

Still further objects of my invention are to improve the machine in various details of construction which will be referred to more fully hereinafter.

In the accompanying drawings consisting of 5 sheets: Figure 1 is a side elevation of my improved sweeping machine. Fig. 2 is a fragmentary side elevation of the rear part of the endless brush and adjacent parts in an inverted or inoperative position. Fig. 3 is a face view of one of the brush sections of the endless carrier. Fig. 4 is a vertical section in line 4—4, Fig. 3. Fig. 5 is a vertical longitudinal sectional elevation of my improved sweeping machine. Fig. 6 is a vertical transverse section in line 6—6, Fig. 5. Fig. 7 is a fragmentary horizontal longitudinal section in line 7—7, Fig. 5. Fig. 8 is a top plan view of the machine. Fig. 9 is a horizontal section, on an enlarged scale, in line 9—9, Fig. 5. Figs. 10 and 11 are vertical transverse sections in lines 10—10 and 11—11, Fig. 5, respectively. Fig. 12 is a fragmentary bottom plan view of the rear part of the sweeping mechanism. Fig. 13 is a fragmentary side elevation of the box of the sweeping machine showing the means for rendering the sweeping mechanism operative and inoperative. Fig. 14 is a fragmentary vertical section, on an enlarged

scale, in line 14—14, Fig. 13. Fig. 15 is a fragmentary side elevation of the box of the machine viewed from the side opposite to Fig. 13 and showing the means for operating the sectional bottom of the box. Fig. 16 is a side elevation of the rear part of the sweeping mechanism viewed from the side opposite to Fig. 1. Fig. 17 is a fragmentary side elevation of the rear part of the sweeping mechanism showing the position of the parts just before the same have been restored to their operative position.

Similar letters of reference indicate corresponding parts throughout the several views.

A represents the box or receptacle of the cart or wagon into which the dirt is swept from the ground or street surface and from which the sweepings are dumped in any suitable place to which the load may be transported. This box may be supported on a running gear of any suitable construction, that shown in the drawings comprising a pair of front steering wheels a , a' and a pair of rear driving wheels a^1 , a^1' . The wagon of the sweeping machine may be propelled in any suitable manner, for instance, by means of draft animals attached to a pole B which connects with the steering wheels. 80 The bottom of the box preferably comprises a plurality of bottom sections C which are arranged in a row lengthwise of the box and each of which is mounted between its front and rear edges on a transverse shaft c 90 which is journaled in bearings c^1 on the adjacent longitudinal walls of the box. Upon turning these bottom sections so that the same are horizontally in line, their edges engage with each other and with the lower 95 edges of the box walls and thereby close the box so that it will retain the dirt which is swept into the same. Upon turning the bottom sections vertically the load in the box is dumped therefrom. The closing 100 movement of the bottom sections is limited by beveling the co-operating edges of the bottom sections and end walls of the box, as shown in Fig. 5. The bottom sections may be turned into their open and closed position by any suitable means but preferably by the means which are shown in Figs. 5, 9 and 15 of the drawings and which comprise a horizontal shaft D journaled lengthwise on one side wall of the box and provided with a plurality of bevel gear pinions 105 d each of which meshes with a gear seg-

ment d^2 on the shaft of one of the bottom sections, an upright shaft D^1 journaled on the front part of the box and connected at its lower end by intermeshing miter gears d^1 5 with the longitudinal shaft D , a handle or wheel E arranged at the upper end of the upright shaft adjacent to the driver's seat E^1 , a spring pressed detent pawl e pivoted on the box and adapted to engage with the 10 ratchet teeth of a detent ratchet wheel e^1 for holding the upright shaft and connecting parts against backward movement so that the bottom sections will not open accidentally and dump the load, and a releasing cam e^2 pivoted on the box and adapted 15 when turned in the proper direction to disengage the detent pawl from the ratchet wheel and permit the bottom sections to be turned open for dumping the contents of 20 the box.

The mechanism whereby the dirt is swept from the street into the box, comprises an endless brush F which has an operative inclined lower part extending from the ground 25 in rear of the box upwardly and forwardly over the rear wall f of the box and adjacent to the front wall f^1 thereof, and an upper inclined inoperative part which extends downwardly and rearwardly from the delivery end to the receiving end of the lower 30 part of the brush. This brush may be variously constructed and consists preferably of two endless chain belts f^2 arranged side by side, and cross bars or transverse stocks 35 f^3 connected at opposite ends with said belts and each provided with outwardly projecting bristles f^4 . At the rear turns of the chain belts the same pass around lower rear sprocket or supporting wheels G which are mounted on a transverse shaft g and at their 40 front turns the same pass around upper front sprocket or supporting wheels H which are mounted on a transverse shaft h journaled in bearings on the adjacent part 45 of the box. Intermediate of the upper and lower sprocket wheels H , G the upper inoperative parts of the brush chain belts are supported by intermediate supporting sprocket wheels I which are mounted on a 50 transverse shaft i journaled in bearings i^1 on the adjacent part of the box.

The endless brush is preferably driven from the axle J of the rear driving wheels a^1 , a^2 of the machine by means of two chain belts j passing around a sprocket pinion j^1 55 on the shaft h of the front supporting wheels H and large intermediate sprocket wheels J^2 adjacent to the ends of the axle J and intermediate gear wheels j^2 operatively connected with the intermediate sprocket wheels J^2 and meshing with gear wheels j^3 60 on the adjacent part of the driving axle J , as shown in Figs. 1, 8 and 10. By this means the endless brush is moved with its lower operative side forwardly and up-

wardly and sweeps any dirt and loose articles on the surface of the road into the top of the box. When it is desired to simply transport the machine without operating the sweeping mechanism, this may be done by 70 disconnecting the driving mechanism of the endless brush from the driving axle. Although various means may be employed for connecting and disconnecting the brush driving mechanism and the driving axle, the 75 means shown in the drawings are suitable and comprise a transverse shaft K carrying the gear wheels j^2 and sprocket wheels J^2 , eccentrics k turning in bearings k^1 on the side walls of the box and provided on one 80 side of their axes with bearings in which the transverse shaft K is journaled, a transverse rock shaft k^2 journaled in the side walls of the box adjacent to the driving axle and provided at opposite ends with forwardly 85 projecting rock arms k^3 , an upright hand lever k^4 , a longitudinal shifting rod or bar k^5 guided in a loop k^6 on the outer side of the box and connected at its front end with the lower arm of the rock lever k^4 , and an 90 intermediate rock arm k^7 arranged on the rock shaft k^2 and connected by a link k^8 with the rear end of the shifting bar k^5 , and links k^9 which connect the rock arms k^3 with arms k^{10} on the eccentrics k , as shown 95 in Figs. 1, 5, 8, 10, 13 and 14. Upon turning the hand lever k^4 forwardly the parts are shifted so as to engage the driven gear wheels j^2 with the driving gear wheels j^3 while upon moving the hand lever k^4 backwardly the parts are shifted in the direction 100 for disengaging the gear wheels j^2 , j^3 .

As the bristles on the lower or operative side of the endless brush move forwardly and upwardly, the dirt on the roadway is 105 picked up by the lowermost part of the brush which engages the roadway and brushed forwardly and upwardly over an inclined runway into the box. This runway preferably comprises a permanently stationary 110 front section L , and a normally stationary rear section L^1 . At the rear end of the rear section L^1 of the runway the same is provided with bearings g^1 in which the shaft g of the rear sprocket wheels G is journaled. Two transverse rows of wings or flaps L^2 , L^3 are pivoted at their front ends on the rear end of the rear runway section and trail at their rear ends on the ground. The wings or flaps are arranged 115 in two groups which are arranged one above the other, the wings of the lower group L^2 being spaced apart and those of the upper group L^3 overlapping the lower wings and bridging the spaces between the 120 same. As the machine is propelled forward over the ground or roadway the wings are free to rise and fall individually to a large extent and adapt themselves to any variation or unevenness of the roadway, thus 125 130

avoiding lifting the entire rear part of the runway when the same engages at one point with a high part of the roadway.

In order to support the rear part of the runway and hold the same a definite distance from the ground a pair of supporting wheels 5 M are provided which run on the ground and are connected with the underside of the rear end of the runway by vertical swivels 10 m so that the same can turn in the manner of casters for adapting themselves to the wheeled running gear or truck of the machine.

For the purpose of bringing the dirt lying 15 in the gutter or next to the curb of the street within the action of the main elevating brush, an auxiliary rotary brush N, N¹ of cylindrical form is provided which is arranged on the curb side of the 20 main brush and at a forwardly inclined angle to the direction of movement of the same, so that when the auxiliary brush turns with its lower side forwardly the dirt in the gutter or next to the curb will be swept 25 into the path of the main brush to be subsequently carried by the latter into the box. The auxiliary brush is mounted on an inclined shaft n which is journaled on the rear ends of the inner and outer arms n¹, n² 30 of a vertically swinging frame which is pivoted on brackets n³, n⁴ on the underside of the adjacent part of the runway. The auxiliary brush may be adjusted vertically to adapt the same to the roadway and for taking 35 up wear by means of an adjusting yoke o connected with the arm n¹ and provided with a slotted lug n⁵ which receives an adjusting screw n⁶ on the adjacent part of the runway, as shown in Figs. 12 and 17. Motion 40 may be transmitted to the auxiliary brush by any suitable means but preferably, as shown in the last mentioned figures, by a horizontal transverse intermediate shaft o¹ journaled on the arms n¹, n², a chain belt o² passing around sprocket wheels o³, o⁴ 45 on the outer end of the intermediate shaft o¹ and the corresponding end of the shaft g of the rear sprocket wheels G, and an intermediate gear wheel o⁵ pivoted on the arm n² 50 and meshing on its opposite sides with gear wheels o⁶, o⁷ on the inner ends of the shafts n, o¹. The outer supporting arm n¹ preferably supports the shaft n between the inner and outer sections N¹, N of the rotary 55 auxiliary brush and also at its outer end for which purpose it extends partly lengthwise in front of the outer brush section N, as shown in Fig. 12. For the purpose of protecting the auxiliary brush against undue 60 wear and also causing any large objects to be directed in front of the same, a guard roller o⁸ is mounted on the arm n¹ adjacent to the outer end of the outer brush section N¹. As the machine advances the guard 65 roller o⁸ upon engaging with the curb saves

the auxiliary brush from wear and it also engages with large obstructions on the road and either deflects them away from the outer end of this brush or in front of the same and thereby prevents injury to the 70 outer end of the same.

In order to prevent the main endless brush upon passing from the lower to the upper side of the same from throwing any dirt adhering thereto over the front wall f¹ of the box and upon the driver's seat E¹, a guard P is provided which is preferably constructed of a sheet of metal secured to said front wall and curving upwardly and rearwardly 75 over the adjacent front part of the main brush. Any dirt which adheres to the main brush and which is thrown forwardly therefrom as it turns around the front supporting wheels H is intercepted by the guard P and directed downwardly by the same into 80 the box.

For the purpose of removing strings, ropes, sticks and other long particles from the main brush, a clearing comb Q is provided which is preferably arranged transversely at the front end of the box, so that the bristles of the main brush sweep through the teeth of the comb and thereby discharge such particles therefrom downwardly into the box. The position of this 90 comb may be adjusted toward and from the brush to suit the length of the bristles and the teeth of the comb and also to compensate for any wear on the same. This adjustment of the comb is preferably effected by mounting the same at opposite ends on arms or levers q which are pivoted to turn vertically on the front wall f¹ of the box and holding the same in position by means of clamping screws q¹ secured to this front wall and passing through segmental slots q² in the supporting arms q, as shown in Figs. 1 and 8. By this means the comb can be adjusted to properly remove any stringy or elongated articles from the main brush so that the 95 same will not become clogged but will be maintained in its best working condition.

For the purpose of rendering the machine more compact for transportation and storage and also to avoid unnecessary wear of the brushes when the machine is propelled while not in use the rear part of the brushing mechanism is folded upwardly and forwardly over the front part thereof. To permit of this folding operation the front and rear sections L, L¹ of the runway are pivotally connected by means of horizontal transverse pins R which are arranged in line and each of which passes through corresponding perforated ears or eyes on the upper ends of a pair of brackets r, r¹ secured to the adjacent ends of the front and rear runway sections on one side thereof. The rear section of the runway and the parts mounted thereon are normally held in their lowermost or 125

operative position by gravity. The pivotal connection between the front and rear runway sections is so located that when the rear section of the runway together with the parts of the sweeper mechanism mounted thereon, is turned upwardly and forwardly to the limit of its movement in this direction these parts are arranged in front of said pivotal connection, as shown by dotted lines 10 in Fig. 5, and are retained in this position by gravity. The rear runway section and the sweeper mechanism mounted thereon may be folded and unfolded by any suitable means but preferably by a pair of gear segments 15 S secured to the brackets r^1 of the rear runway section, and a transverse shaft s journaled in bearings on the underside of the front runway section and provided with gear pinions s^1, s^2 meshing with said gear segments. The shaft s may be turned by means of a crank applied to one end thereof or any other suitable means. In its uppermost position the rear runway section is supported by means of stops or legs t secured thereto and resting on stops or standards t^1 arranged on the front runway section, thereby holding the parts reliably in position. Upon folding the endless brush the same, in the absence of any provision to 30 prevent it, would be liable to move backwardly owing to the weight of the loop in the upper part thereof, which backward movement would injure those bristles of the endless brush which are in engagement with the runway, inasmuch as they would be bent into a reverse angular position. To prevent this a locking device, preferably automatic in its operation, is provided which comprises a dog u pivoted on one side of the rear runway section adjacent to one of the chain belts of the endless brush and a weighted arm u^1 connected with the pivot of the dog. The relative arrangement of the parts is such that when the rear runway section and 40 endless brush are lowered the dog u is disengaged from the adjacent brush chain belt, as shown in Fig. 1, thereby permitting the endless brush to travel freely. But when the rear runway section is turned upwardly into a reversed or folded position the weighted arm u^1 operates to automatically turn the dog u into engagement with the adjacent brush belt chain and hold the brush against backward movement.

50 In the absence of any provision to prevent it, the wings or flaps at the rear end of the rear runway section would hang in a vertical or pendent position upon lowering the rear end of the endless brush to its operative position and become broken by engaging the surface of the roadway in this position. To overcome this, means are provided which comprise a plurality of retaining fingers V arranged lengthwise underneath the rear runway section and having their rear ends

adjacent to the underside of the lower set or group of wings or flaps, a set of rear links v whereby these fingers are suspended midway of their length from the underside of the rear runway section, a transverse rock shaft W journaled on the underside of the rear runway section and provided with a plurality of depending rock arms w each of which is pivotally connected with the front end of one of said retaining fingers and a weighted arm w^1 connected with one end of the rock shaft W . In the lowered position of the rear parts of the runway and endless brush the weight arm w^1 is turned on the rear side of its axis and withdraws the rear ends of the retaining fingers sufficiently to clear the wings and permit the latter to rise and fall freely in following the uneven surface of the street or roadway which is being swept. Upon inverting the rear parts of the runway and main brush the weight arm w^1 turns to the opposite side of its pivot and moves the retaining fingers against the underside of the lower set of wings and thereby holds the same together with the upper set of wings close to the bristles of the endless brush, as shown in Fig. 2. The wings are retained in this position until the rear runway section and adjacent parts have nearly reached their lowermost or operative position and the wings while in an inclined position engage at their rear ends with the roadway, as shown in Fig. 17. When the parts reach this position the weight arm w^1 again shifts to the rear of its center, as shown in this figure, thereby again withdrawing the retaining fingers from the wings so that as the rear runway section completes its downward movement the wings will be free to rise and fall without interference from said fingers. When the lower or rear runway section is raised for folding the endless brush into an inoperative position, the joint between the front and rear runway sections opens, whereby any dirt present at this place on the runway drops. In order to prevent such dirt from falling on the swept part of the street a catch pan or tray y is provided which is arranged below the runway and extends across the joint between its sections and is secured at its front end to the front runway section. As the rear runway section is raised and dirt drops through the joint between the same and the front section this dirt is caught by the pan y from which it may be removed by the operator, thereby avoiding littering the street after being swept.

I claim as my invention:

1. A sweeping machine comprising a box, an endless sweeping brush extending forwardly and upwardly over said box, and means for folding the rear part of said brush forwardly over the front part thereof.
2. A sweeping machine comprising a box,

an inclined runway extending to the rear end of said box and having a stationary front part and vertically swinging rear part, an endless sweeping brush extending over 5 said runway and box, front supporting wheels mounted on the box and supporting the front end of the endless brush, and rear supporting wheels mounted on the rear section of the runway and supporting the rear 10 end of the endless brush.

3. A sweeping machine comprising a box, an inclined runway extending to the rear end of said box and having a stationary front part and vertically swinging rear part, 15 an endless sweeping brush extending over said runway and box, front supporting wheels mounted on the box and supporting the front end of the endless brush, rear supporting wheels mounted on the rear section 20 of the runway and supporting the rear end of the endless brush, and means for turning the rear runway section together with the parts carried thereby comprising a gear segment connected with the rear runway section and a rotatable pinion mounted on the 25 front runway section and meshing with said segment.

4. A sweeping machine comprising a box, an inclined runway arranged at the rear end 30 of said box and having a vertically swinging rear section, an endless sweeping brush movable forwardly over said runway means for folding the rear part of said brush over the front part thereof, and a lock for holding said brush against backward movement, 35 while in its folded condition.

5. A sweeping machine comprising a box, an inclined runway arranged at the rear

end of said box and having a vertically swinging rear section, an endless sweeping brush movable forwardly over said runway, and an automatic lock mounted on the rear runway section and adapted to hold said brush against lengthwise movement in the elevated position of said rear runway section and to release said brush in the depressed position of the rear runway section. 45

6. A sweeping machine comprising a box, an inclined runway arranged at the rear end of said box and having a vertically swinging rear section, an endless sweeping brush movable forwardly over said runway and having a chain belt, a dog pivoted on the rear runway section adjacent to said belt, and a weighted arm connected with said 50 dog and adapted to move the same into engagement with said chain belt upon elevating said rear runway section and to clear said chain belt upon depressing the rear runway section. 55

7. A sweeping machine comprising a box, a runway extending to the rear end of said box and having a stationary front section and a vertically swinging rear section which is pivotally connected with the front section, 60 an endless sweeping brush moving forwardly over the runway, and a pan extending across the joint between said runway sections and below the same and secured to the front section. 70

Witness my hand this 3rd day of January 1910.

LOUIS SOOS.
